DESIGN FOR A COMBINATION MIRROR AND DIRECTION INDICATOR

Louis Roland Soderberg, Great Neck, N. Y.

Application March 17, 1939, Serial No. 83,641

Term of patent 7 years

To all whom it may concern:

Be it known that I, Louis Roland Soderberg, a citizen of the United States, residing at Great Neck, in the county of Nassau, in the State of New York, have invented a new, original, and ornamental Design for a Combination Mirror and Direction Indicator, of which the following is a specification, reference being had to the accompanying drawing, forming part thereof.

Figure 1 is a front elevation of a combination

mirror and direction indicator showing my new design;

Figure 2 is a rear elevation of the combination mirror and direction indicator; and

Figure 3 is a plan view of the same.

I claim:

The ornamental design for a combination mirror and direction indicator, substantially as shown.

LOUIS ROLAND SODERBERG.
